CLAIM

The ornamental design for a vehicle windshield, as shown and described.

DESCRIPTION

FIG. 1 is a frontal perspective view of a vehicle windshield showing our new design;

FIG. 2 is a left side elevational view thereof;

FIG. 3 is a front elevational view thereof;

FIG. 4 is a left side elevational view thereof;

FIG. 5 is a right side elevational view thereof;

FIG. 6 is top down plan view thereof;

FIG. 7 is bottom up plan view thereof;

FIG. 8 is sectional view taken along the lines 8—8 in FIG. 3;

FIG. 9 is an alternative front elevational view the vehicle windshield showing a ceramic paint applied to the inner surface thereof;

FIG. 10 is a left side elevational view thereof;

FIG. 11 is a right side elevational view thereof;

FIG. 12 is a top down plan view thereof; and,

FIG. 13 is a bottom up plan view thereof.

The broken lines shown in the drawings are for illustrative purposes only and form no part of the claimed design. The various views are not to scale.
